UNITED STATES PATENT OFFICE.

WILLIAM W. RONEY, OF SEWICKLEY, PENNSYLVANIA, ASSIGNOR TO H. H. ROBERT-
SON COMPANY, OF PITTSBURGH, PENNSYLVANIA, A CORPORATION OF PENNSYL-
VANIA.

EXPANSIBLE MANDREL.

Application filed June 25, 1920. Serial No. 391,800.

To all whom it may concern:

Be it known that I, WILLIAM W. RONEY, a citizen of the United States, residing in Sewickley, in the county of Allegheny and

5 State of Pennsylvania, have invented an Improvement in Expansible Mandrels, of which the following description, in connection with the accompanying drawings, is a specification, like characters on the drawings representing like parts.

This invention relates to an expansible and contractible mandrel, especially designed and adapted among other uses to be employed with rolls of paper or like fibrous material.

15 The invention has for its object to provide a mandrel of the character described, which is non-collapsible by strain placed upon it by the paper or like material.

20 The invention further has for its object to provide at a minimum cost a mandrel of minimum weight and size and of maximum expansibility.

To this end, the mandrel is provided with 25 preferably a plurality of movable members mounted on a shaft or supporting member, and with means for effecting movement of said movable members.

These and other features of this invention 30 will be pointed out in the claim at the end of this specification.

Fig. 1 is a plan view of an expansible mandrel embodying this invention in its contracted condition.

35 Fig. 2, a like view with the mandrel in its expanded condition.

Fig. 3, a cross section of a roll of paper and of the mandrel shown in Fig. 1 inserted therein.

40 Fig. 4, a cross section of the roll of paper with the mandrel expanded to grip the same.

Figs. 5 and 6, enlarged views of the mandrel shown in Figs. 3 and 4 in its contracted 45 and expanded position respectively, and

Figs. 7 and 8, like views of a modified form of mandrel.

Referring to the drawing, *a* represents a 50 shaft or rod which constitutes a supporting member for one or more, preferably four movable members *b*, each of which is made as a substantially flat bar which is attached to a straight or flat side or surface 10 of the shaft or rod *a* between the ends of the latter.

The flat bars *b* are secured to the shaft or rod *a* so as to move therewith and also to be moved laterally thereon so as to project beyond the shaft or rod *a*.

In the present instance, each bar *b* is secured to the shaft *a* by screws 12 extended through inclined slots 13 in the bar, which slots are preferably enlarged or countersunk at 14 to receive the heads of the screws, so that the said heads may be flush with the 65 outer surface of the bar *b*.

In the contracted position of the bars *b*, the screws 12 are at the extreme right hand end of the slot 13, and in the extreme expanded position of the bar shown in Figs. 70 2 and 6, the screws are at the left hand end of the slots.

The bars *b* are positively moved lengthwise of the shaft *a* in one direction by a nut or internally threaded hub 15 of a hand wheel 16, which nut is in threaded engagement with a threaded portion 17 of the shaft *a*, and while said bars are being moved longitudinally, they are also moved outwardly or laterally. The nut or hub 15 is provided 75 at its front end with an annular recess 19 into which the rear ends of the bars *b* are extended, and said ends are preferably reduced in width by cutting off one corner of the bars as clearly shown in Figs. 1 and 2. 85

The bars *b* may be moved in the opposite direction by gravity when the hand wheel is turned in the reverse direction to release the bars *b*, or they may be restored to their normal position by the resistance offered by 90 the paper when the shaft *a* is moved forward after the bars are released by the nut 15.

By extending the ends of the bars into the recess 19, they are prevented from being 95 curled or bent upwardly by the pressure of the hand wheel upon them especially as the resistance offered by the paper increases.

The front ends of the gripping bars *b* may be rounded as at 22 to facilitate entrance 100 into the opening 23 at the center of the paper roll 24.

The bars *b* are preferably made of a length substantially equal to the width of the roll 24 and the shaft *a* may be provided 105 at one end with collars 25 which are spaced apart and are designed to position the shaft in its bearing at that end.

The opposite end of the shaft *a* may be rounded to avoid tearing the paper when 110

the mandrel is inserted into and through the opening 23 in the roll.

The mandrel shown in Fig. 1 is especially serviceable as an unwinding mandrel, that is, to support a roll of paper while the latter is being unwound. When so used, the mandrel in its contracted condition shown in Fig. 1 is inserted into and through the roll and the hand wheel 16 is turned to move the bars *b* forward and laterally and to cause them to be embedded in the paper after the manner illustrated in Fig. 4, and thereby firmly grip the roll at a plurality of points for the width of the roll.

15. It will be observed that when the mandrel is thus expanded into firm engagement with the paper roll, the latter can be unwound until a minimum number of convolutions are left on the mandrel and until substantially all of the paper roll has been unwound, as the gripping members or bars *b* of the mandrel are positively held in their expanded position and are locked against reverse movement by the strain placed upon them by the tension on the paper as it is unwound from the roll.

When the convolutions of the roll have been reduced to a few, the convolutions remaining on the mandrel may be severed from the unwound portion of the paper; the hand wheel is turned back, and the mandrel is then removed from its bearings and placed in an upright position with the pointed end uppermost to permit the gripping members to be moved by gravity into their contracted position shown in Fig. 1.

The gripping members *b* may also be moved into their closed position while the mandrel is in a horizontal position by backing off the hand wheel so as to release the gripping bars or members *b*, and then moving the shaft *a* forward to cause the screws 12 to travel in the slots 13 to the right hand

end thereof, the gripping bars *b* being held from movement by the paper or by the hand of the operator.

The mandrel shown in Figs. 1 to 6 is especially designed to be used as an unwinding mandrel and while it may also be used as a winding mandrel, it is preferred in the latter case to provide the members or bars *b* with arms 30 (see Figs. 7 and 8), which extend substantially at right angles to the bars *b* with the arm of one bar overlapping the next adjacent bar, and with the arms provided with transversely curved outer surfaces 31, so as to present a smooth and substantially circular mandrel upon which the paper or like material may be wound.

The arms 30 may be provided with openings 32, indicated by dotted lines, by means of which access may be had to the screw 12 in line therewith.

Claim.

In a mandrel of the character described, in combination, a supporting shaft provided with a screw-threaded portion and with a plurality of substantially flat portions between its ends, substantially flat bars co-operating with the flat portions of said shaft and provided with inclined slots, screws extended through said slots into said shaft to cause the flat bars to slide outwardly and transversely with relation to the shaft upon said flat portions as bearing surfaces when said flat bars are moved longitudinally of the shaft, and a hand wheel provided with a threaded hub engaging the threaded portion of said shaft and having an annular recess into which the rear ends of said bars extend and co-operating with the threaded hub to be moved thereby when the hub is rotated in one direction upon the shaft.

In testimony whereof, I have signed my name to this specification.

WILLIAM W. RONEY.
